(57) **CLAIM**

The ornamental design for a cap, as shown and described.

DESCRIPTION

FIG. 1 is a front, right perspective view from above of a cap, showing the new design;

FIG. 2 is a rear, left perspective view from above of the cap; FIG. 3 is a front, right perspective view from below of the cap;

FIG. 4 is a rear, left perspective view from below of the cap;

FIG. 5 is a front elevation view of the cap;

FIG. 6 is a rear elevation view of the cap;

FIG. 7 is a right side elevation view of the cap;

FIG. 8 is a left side elevation view of the cap;

FIG. 9 is a top plan view of the cap; and,

FIG. 10 is a bottom plan view of the cap.

The portions shown in shorter dashed lines represent stitching on the cap and form part of the claimed design.

The portions of the cap shown in longer dashed lines along the rear opening and strap closure form no part of the claimed design.

1 Claim, 9 Drawing Sheets
